UNITED STATES PATENT OFFICE.

KARL FOUSEK, OF AUSTIN, TEXAS.

SANITARY CUSPIDOR.

1,076,204.

Specification of Letters Patent.

Patented Oct. 21, 1913.

Application filed August 11, 1913. Serial No. 784,170.

To all whom it may concern:

Be it known that I, KARL FOUSEK, a citizen of the United States, residing at Austin, in the county of Travis and State of 5 Texas, have invented a new and useful Improvement in Sanitary Cuspidors, of which the following is a specification.

This invention relates to a sanitary cuspidor which is normally kept closed and 10 which when opened will return automatically to closed position.

The invention consists of the novel features of construction hereinafter described, pointed out in the claims and shown in the 15 accompanying drawing, in which—

Figure 1 is a sectional elevation, parts being shown in closed position. Fig. 2 is a similar view parts being shown in open position.

20 In these drawings 1 represents an ornamental base of any suitable kind provided with a centrally arranged hollow standard 2, which supports a semispherical vessel 3, said vessel being provided adjacent its upper rim 25 with an inwardly extending annular flange 4. Working within the standard 2 is a suitable post 5 longitudinally slotted from its lower end as indicated at 6, for a purpose which will appear hereafter. This standard carries a semispherical cuspidor 7, of 30 less size than the vessel 3 and also retained within said vessel. The cuspidor 7 is provided with a concavo-convex top member 8 centrally cut-out as shown at 9. A semi-

35 spherical shell 10 divided into two halves acts as a cover for the cuspidor, and the said halves of the shell being pivotally connected to small stub shafts 11 carried by the interior shell of the receptacle 3, and each 40 half of the shell is provided upon each side with an arm 12, the arms of the two halves of the shell crossing as clearly indicated by the dotted lines of Fig. 1. These arms terminate in hook members which 45 respectively engage pins 13, carried by the exterior of the cuspidor 7.

To operate the device I slot opposite sides of the standard 2 to form lugs 14 adjacent said slots and pivot to said lugs foot 50 treadles 15, the entire ends of the treadle

members intersecting within the slot 6 of the post 5, and being slotted to engage a pin 16 arranged transversely with respect to said slot. Normally the parts will remain in the position shown in Fig. 1, but 55 upon applying foot pressure to either of the treadles 15 the post 5 will be lifted thus elevating the cuspidor 7 and the two members of the shell 10 will swing into open position by reason of the pressure of the 60 pins 13 upon the arms 12. Such opening movement will be facilitated by the action of gravity after such movement of the shell members will be limited in either direction by means of flanges 17 coming into engagement with the flange 4. Upon releasing the foot treadle the weight of the post 5 and cuspidor 7 will cause them to drop automatically into the position shown in Fig. 1 65 and the pins 13 are at all times in engagement with the arms 12, the shell members will thus be automatically closed.

In order to prevent too rapid descent of the post 5 I provide an inlet upon one side of the standard 2 controlled by an inwardly 70 opening check valve 18 and a very small discharge outlet 19 upon the opposite side of the standard. As the post 5 rises air will enter rapidly through the valve controlled inlet but will escape comparatively 75 slow through the small inlet thereby forming an air cushion checking too rapid a descent of the cuspidor.

What I claim is:

1. A device of the kind described comprising a standard having a receptacle thereupon, a post vertically movable in the standard, a cuspidor carried by the post, said cuspidor normally occupying a position within said receptacle, foot operated 85 means for elevating said post, a shell divided into two portions and adapted to normally close the said receptacle, and means carried by the cuspidor for opening said shell upon rising movement of the cuspidor 90 within the receptacle.

2. A device of the kind described comprising a standard, a semispherical receptacle carried thereby, a post vertically movable in the standard, a cuspidor carried by 100

the post, a shell divided into two halves, each of said halves being pivotally mounted in said receptacle, said shell members being adapted to come together when in closed position and to slide within said receptacle when in open position, arms carried by said shell members, and pins carried by the cus-

pidor and always in engagement with said arms as and for the purpose set forth.

KARL FOUSEK.
